UNITED STATES PATENT OFFICE

MAX GRUNBAUM, OF BROOKLYN, NEW YORK

CELLULAR PRODUCT AND METHOD OF MAKING THE SAME

No Drawing.

Application filed May 8, 1928. Serial No. 276,203.

This invention relates to cellular products such as paper, wall paper, paper board, paste board and like materials produced from paper or like cellular pulp, containing as a constituent part thereof an insecticidal, germicidal and fungicidal material which is non-odorous, non-poisonous, or substantially or relatively non-poisonous to mammals and which can be added to the pulp from which such products are made without causing any material deterioration thereof and which is substantially unaffected in the process of producing such products from the pulp treated therewith.

15 The invention is more particularly concerned with paper, paper board, paste board, and like materials produced from paper, but primarily wall paper, treated in accordance with this invention to render such products insect, germ and fungus proof. The invention also relates to the process of producing such insect, germ and fungus proof products.

It is well known that for many uses paper and other cellular products of the character referred to above have been found to be highly objectionable because of the fact that such products are subject to injurious attack by insects and fungi and also because certain paper or pulp products such as wall board and wall paper are unsanitary and provide breeding places for germs, insects and the like. These objectionable features, particularly the latter in regard to wall paper, have resulted in the discontinuance of the use of certain 35 paper products with consequent loss to manufacturers of such products.

I have discovered that these objectionable features can be obviated and that satisfactory insect, germ, and fungus proof products can 40 be made by incorporating a non-odorous insecticide, germicide and fungicide which will not injure or be injured by paper or like pulp with the materials from which the products are to be produced, before forming the products or applying such protective material to the finished product. I prefer to employ an organic insecticide, germicide and fungicide and of such organic insecticides I prefer to use an organic insecticide which has been derived from the bark of the cinchona tree here-

inafter referred to as a cinchona derivative. Among the materials so derived and which are particularly adapted for use in the practice of my invention, may be mentioned quinine, quinidine, cinchonine and cinchonidine. 55 Although all of these materials, or any one of them, may be employed with success, I prefer to use cinchonine ($C_{20}H_{24}N_2O$) or its salts. These materials, in addition to being odorless insecticides are germicides and fungicides as well, and are non-poisonous or at the most only slightly poisonous to mammals. The taste of these materials is extremely bitter and offensive.

60 In the preferred practice of my invention I mix about 0.04 of a pound of cinchonine with each 100 pounds of the cellular material which forms the stock from which the insect proof article is to be produced. After adding the insecticide to the pulp or stock, the paper, paper board, wall paper, paste board or the like is produced in any usual or desired manner and the product is not deleteriously affected by the presence of the cinchonine and the cinchonine is not deleteriously affected by the process of producing the paper or the like from the thus treated pulp.

65 In producing paper and like products which are insect proof, germ proof and fungus proof according to my process, the insecticide may not only be added to the materials from which the paper, paste board or the like is to be formed but it may be added to the clay or other filler or size which may be employed in or upon the surface of the paper or the like. In addition, the protective material may be incorporated in the coating material when so-called "coated papers" are being produced. Also, in the case of wall paper and other paper products which are substantially completely covered with a printed design I may advantageously incorporate the protective material in the printing ink and impregnate the paper product with such material during the printing thereof.

70 75 80 85 90 95 In place of cinchonine or other cinchona derivative I may with some measure of success employ sodium fluorid or a silicofluoride but I prefer to use a cinchona derivative.

100 As heretofore stated, my invention is pref-

- erably employed in the manufacture of wall described having cinchonine incorporated paper and like cellular wall coverings and therein.
when so used the cinchonine or equivalent material is preferably added in the proportions set forth to the pulp, filler, size, printing ink or the like used in producing the wall covering.
- 5 My invention is also particularly adapted for use in preparing paper products for packaging food and other materials which 10 are subject to deterioration due to the attacks of insects, germs, fungi and the like.
- 15 While I have described in detail the preferred practice of my process and the materials which I prefer to employ it is to be understood that I am not limited thereto except as set forth in the subjoined claims.
- I claim:
- 20 1. The herein described process of making products produced from cellular material insect proof, which comprises incorporating a cinchona derivative therein.
- 25 2. The herein described process of making products produced from cellular material insect proof, which comprises incorporating a compound of the quinine group therein.
- 30 3. The herein described process of making products produced from cellular material insect proof, which comprises incorporating cinchonine therein.
- 35 4. The herein described process of making insect proof, germ proof and fungus proof wall paper and like cellular material which comprises adding a cinchona derivative to the material from which such products are formed, and forming the paper and like cellular material therefrom.
- 40 5. The herein described process of making insect proof, germ proof and fungus proof wall paper and like cellular material which comprises adding a compound of the quinine group to the material from which such products are formed, and forming the paper and like cellular material therefrom.
- 45 6. The herein described process of making insect proof, germ proof, and fungus proof wall paper and like cellular material which comprises adding cinchonine to the material from which such products are formed, and forming the paper and like cellular material therefrom.
- 50 7. The herein described process of producing insect proof paper comprising adding a cinchona derivative to the material from which such products are produced, and forming the paper therefrom.
- 55 8. The herein described process of producing insect proof paper comprising adding cinchonine to the material from which such products are produced, and forming the paper therefrom.
- 60 9. A cellular product of the character described having a cinchona derivative incorporated therein.
- 65 10. A cellular product of the character

In testimony whereof I affix my signature.

MAX GRUNBAUM.
